UNITED STATES PATENT OFFICE.

TILGHMAN E. BRANSON, OF BELLE PLAINE, KANSAS, ASSIGNOR OF ONE-THIRD TO HARRY HATFIELD AND ONE-THIRD TO W. S. FOSTER, OF BELLE PLAINE, KANSAS.

GRAIN-DOOR FOR CARS.

No. 838,503.

Specification of Letters Patent.

Patented Oct. 16, 1906.

Application filed March 23, 1905. Serial No. 251,667.

To all whom it may concern:

Be it known that I, TILGHMAN E. BRANSON, a citizen of the United States, residing at Belle Plaine, in the county of Sumner and State of Kansas, have invented a new and useful Grain-Door for Cars, of which the following is a specification.

The invention relates to improvements in grain-doors for cars.

The object of the present invention is to improve the construction of grain-doors for cars, more especially that shown and described in Patent No. 687,618, granted to me the 26th day of November, 1901, and to provide simple, inexpensive, and efficient means for enabling grain-doors of loaded cars to be easily lifted without the use of crowbars, levers, and other tools tending to destroy or otherwise injure a grain-door, and thereby facilitate the preservation of the latter and at the same time prevent leaks and effect a great saving in time.

A further object of the invention is to provide grain-door-operating mechanism which will be entirely out of the way when not in use and which may be conveniently operated from the exterior for partially opening a grain-door to relieve the latter of the pressure of the grain.

Another object of the invention is to provide door-lifting mechanism adapted for use on various kinds of doors to effect such partial opening without injuring either the grain-door or the car.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a longitudinal sectional view of a portion of a car provided with a grain-door constructed in accordance with this invention and shown closed. Fig. 2 is a transverse sectional view, the parts being arranged as shown in Fig. 1. Fig. 3 is a longitudinal sectional view, the grain-door being open. Fig. 4 is a transverse sectional

view, the parts being arranged as shown in Fig. 3. Fig. 5 is an enlarged detail view taken longitudinally of one of the door-lifting devices and illustrating the manner of slidably mounting the same. Fig. 6 is an enlarged detail view of one of the slidable door-carrying shoes. Fig. 7 is a detail perspective view of one of the guides for the door-carrying shoes. Fig. 8 is a detail sectional view illustrating the manner of locking the upper end of the fastening-bars.

Like numerals of reference designate corresponding parts in all the figures of the drawings.

1 designates a grain-door composed of flexible sections or panels 2, pivotally connected by hinges 3 like those shown and described in the said patent. The grain-door is slidably connected with guide rods or tracks 4, located at opposite sides of the doorway 5 of a freight-car 6, as clearly shown in Fig. 1 of the drawings. The upper sections or panels of the grain-car door are not connected with the guide rods or tracks, and the lower and intermediate sections or panels are provided with hooks 7 and eyes 8. The eyes are arranged on and connect the grain-door to the guide rods or tracks, which terminate short of the bottom 9 of the car and which have their lower portions 10 bent laterally at right angles and provided with terminal ears or flanges 11, which are bolted or otherwise secured to the side of the car. Each side of the car, as clearly shown in Fig. 2 of the drawings, is provided with a grain-door, and the guide rods or tracks, which are located at opposite sides of each doorway 5, have lower vertical guiding portions and upper curved or arched portions, which are secured to the roof of the car at the median line thereof. The hooks of the lower sections are adapted to slide on the guide rods or tracks when the grain-door is moved upward from the position shown in Figs. 1 and 2 to that illustrated in Figs. 3 and 4, and they are adapted to slide off the same when the grain-door is closed.

By this construction the lower portion of the grain-door is slidably connected with the guide rods or tracks when the grain-door is raised, and at the same time the means for slidably connecting the door with the guide rods or tracks do not interfere with the particular construction of the lower ends of the same.

The flexible grain-door is rigidly clamped in its closed position by vertical fastening-bars 12, arranged across the ends of the sections or panels and having their lower terminals fitted in sockets 13 of the floor 9, and their upper ends are provided with locking devices consisting of rods or bolts 14, each provided at one end with a hook 15 and having its other end threaded for the reception 10 of a winged nut 16. The rods or bolts pierce the upper ends of the fastening-bars, and the hooks are adapted to engage fixed portions 17 of the car. The fixed portions consist of transverse pins arranged in recesses 18 of the 15 sides of the car. The recesses 18 are located at opposite sides of the doorway and are covered by face-plates 19, having slots through which the hooks of the rods or bolts are passed. When the fastening-bars are 20 arranged as shown in Fig. 1, the nuts are screwed tightly against the clamping-bars, and the grain-door is firmly locked in its closed position. The locking devices are carried by the fastening-bars, which are held 25 when not in use against the sides of the car by supports or brackets 20 and 21. The supports 21 consist of angularly-bent plates secured at their upper and lower portions to the sides of the car, forming loops for the 30 lower ends of the fastening-bars. The supports 20 are open at the top and consist of plates or brackets having lower attachment portions and substantially L-shaped upper supporting portions. The upper ends of the 35 attachment-bars are connected by chains 22 with the open supports or brackets to prevent the fastening-bars from becoming accidentally lost or mislaid. The chains are provided with plates which are secured to the upper 40 ends of the fastening-bars by the rods or bolts and the nuts thereof. When the fastening-bars are arranged in the supports or brackets, they are entirely out of the way. The lower ends of the fastening-bars are provided with 45 projecting lips or flanges 23, which are adapted to interlock with face-plates 24, arranged over the sockets 13 of the floor of the car. The lower ends of the fastening-bars may be readily introduced into the sockets by tilting 50 or inclining the fastening-bars inwardly toward the center of the car. The interlocking of the lower ends of the fastening-bars with the floor of the car effectually prevent any accidental upward movement of the bars, 55 and they cannot when in a vertical position become disengaged from the sockets. These lips or projecting portions 23 may, however, be omitted, if desired, as the grain-door is firmly held against vertical movement by 60 wedges 23^a, interposed between the upper edge of the grain-door and the rods or bolts. When the wedges are driven into position, there is no liability of the parts becoming accidentally unfastened through any jar or vibration of the car. When the wedges are with- 65

drawn, the fastening-bars may be readily removed.

The grain-door is provided at its top with a loop or handle 25, adapted to be engaged by a holding device 26 for retaining the grain-door in an elevated position at the top of the car, as clearly shown in Figs. 3 and 4. The holding device consists of a short chain secured at one end to the top of the car and provided at its other end with a hook for engaging the loop 25. A loop 27 is also arranged at the top of the car for holding the free end of the chain when the latter is not in engagement with the grain-door.

In order to obviate the inconvenience of 80 and the damage resulting from forcing grain-doors partially open by means of crowbars, levers, or the like, a pair of grain-door carriers 28 is employed. These grain-door carriers or shoes consist of vertical slides 29, provided at their lower ends with projecting supporting portions or feet 30, normally located flush with the upper face of the floor of the car and arranged to engage the lower edge of the grain-door, which is reinforced by 85 a metal bar or strip. These slides are arranged in guides or ways 31, constructed of metal and let into the sides of the car, as clearly shown in Fig. 5 of the drawings. Each guide consists of a back 32 and parallel side walls 33, the upper portions of the side walls being provided with inwardly-projecting front flanges 34, extending over the front or exterior of the slides and retaining the same in the guides. The front flanges 90 terminate short of the lower ends of the guides to provide open spaces to admit of the necessary vertical movement of the projecting portion or foot 30. The upper ends of the slides are provided with perforated 95 flanges or ears 35, to which are connected the lower ends of wire ropes or cables 36; but chains or any other suitable flexible connections may be employed. The wire ropes or 100 cables extend upward to a pair of drums 37 of a windlass-shaft 38, journaled in suitable bearings of brackets 39, which are secured to the sides of the car at opposite sides of the top of the doorway. The car is provided at 105 opposite sides of the doorway with grooves 110 31^a, extending upward from the guides or ways 31 to receive the flexible connections to enable the same to clear the sides of the car. The windlass-shaft is adapted to be rotated 115 for winding the wire ropes or cables on the drums, and for this purpose a ratchet device is employed, consisting of a ratchet member or section 40, preferably formed integral with one of the drums and arranged at the inner 120 end thereof and adapted to be engaged by a ratchet member 41, having a ratchet-face for 125 engaging the ratchet section or member 40. The ratchet section or member 41, which is loosely arranged on the shaft, is provided with an operating arm or handle 42, and it 130

is held in engagement with the section or member 40 by a coiled spring 43, disposed on the shaft and interposed between the section 41 and an adjustable collar 44, which is secured to the shaft by a clamping-screw and which is adapted to be adjusted thereon to vary the tension of the spring. By oscillating the operating arm or lever 42 the windlass-shaft is continuously rotated and is adapted to move the grain-door carriers vertically for partially opening the grain-door. By this construction the grain-door may be conveniently opened a sufficient distance to relieve the grain-door of the pressure of the grain, and after the door is free from such pressure the lifting mechanism may be returned to its initial position. When the slideable ratchet section or member 41 is disengaged from the ratchet-section 40 and the pawl 45 is disengaged from the ratchet-wheel 46, the weight of the grain-door carriers will unwind the flexible connections from the drums and the parts will return automatically to their initial position. The ratchet-wheel is mounted on the shaft at one end thereof, and the pawl, which is pivoted above the shaft, is adapted to engage the ratchet-wheel to prevent retrograde rotation of the shaft. The grain-door may then be raised by hand and secured at the top of the car by means of the holding device 26, as before explained. Prior to lifting the grain-door the wedges are removed and the locking devices are disengaged from the side of the car or are loosened sufficiently to permit the door to move. The grain-door is adapted to be raised and lowered independently of the lifting mechanism, which may be employed for starting various kinds of grain-doors. Instead of employing the hoisting mechanism shown in the accompanying drawings various other means may be provided for operating the carriers. The car is provided with the usual slideable car-doors 47, as clearly indicated in Fig. 2 of the drawings.

It will be seen that the mechanism for raising the grain-door is adapted to partially open a grain-door when the same is subjected to pressure and without injuring either the car or the door, thereby preventing the leaks which result from such injury and at the same time increasing the durability of the door. Also the device is adapted to effect a great saving in time and lessens the labor incident to the operation of grain-doors. Also it will be clear that the lifting mechanism is entirely out of the way when not in use and that it is applicable to various kinds of grain-doors.

Having thus fully described my invention, what I claim as new, and desire to secure by Letters Patent, is—

1. The combination with a vertically-

movable door, of means for partially raising the same, said means embodying a vertically- 65 movable support which engages beneath the door when the latter is in its lowered position and carries the door to its raised position, said support being separable from the door so as to permit the door to have a continued 70 independent movement after the partial raising of the door has been effected and when the support has dropped back to its normal position at the bottom of the car, and a guide for retaining the support in sliding 75 engagement with the door-frame.

2. The combination with a door, of a vertically-slidable carrier guided on the car and having a supporting-foot extending beneath the door when the latter is in its closed position and constructed to raise the door to a predetermined point, said foot detachably engaging the door so as to permit the door to have a continued independent movement 80 after the foot has dropped back to its normal 85 position at the bottom of the car, means for raising the carrier, and means for retaining the carrier in sliding engagement with the door-frame.

3. The combination of a car having a door 90 way and provided at opposite sides with guides, a door, and hoisting mechanism having carriers slideable in the guides and provided with supporting portions or feet arranged to normally engage beneath the lower 95 edge of the door when the latter is in its closed position for raising the same to a predetermined point, said feet having a detachable engagement with the door so as to permit the door to have a continued independent movement after the feet have dropped back to their normal position at the bottom 100 of the car.

4. The combination with a door, of opposite guides comprising a back, side walls, 105 and inwardly-extending flanges terminating short of the lower ends of the guides, carriers operating in the guides and provided with projecting portions or feet detachably receiving the door, and means for raising the carriers. 110

5. The combination of a car having a doorway and provided with opposite guide-rods terminating short of the floor of the car and secured to the sides thereof, and a door provided with eyes receiving the guide-rods, said door being also provided at its lower portion with hooks arranged to run on the guide-rods and adapted to slide off the same. 115

In testimony that I claim the foregoing as 120 my own I have hereto affixed my signature in the presence of two witnesses.

TILGHMAN E. BRANSON.
